UNITED STATES PATENT OFFICE.

JULIUS PEGEL, OF PHILADELPHIA, PENNSYLVANIA, ASSIGNOR TO JOHN BROMLEY & SONS.

DESIGN FOR A RUG.

SPECIFICATION forming part of Design No. 20,435, dated December 23, 1890.

Application filed August 30, 1890. Serial No. 363,560. Term of patent 3½ years.

To all whom it may concern:

Be it known that I, JULIUS PEGEL, a subject of the Emperor of Germany, residing in the city of Philadelphia, State of Pennsylvania, have invented and produced a new and original Design for a Rug, of which the following is a full, clear, and exact description, reference being had to the accompanying drawing, forming a part of this specification.

My invention has relation to the surface ornamentation of a rug; and it consists of the design therefor shown in the accompanying photographic illustration hereto annexed and to which reference is made.

The distinguishing features of the design are the inner rectangular border (marked B) and between it and the edge of the rug a series of disconnected leaf figures constituting

an outer border, (marked A.) The ornamental figures of varied shapes within the field center (marked C) may be varied or omitted, as desired, without departing from the general plan of the design.

I claim as my invention—

1. The design for a rug, substantially as shown and set forth.
2. The design for a rug, consisting of the parts A and B, substantially as shown and set forth.

In testimony whereof I have hereunto affixed my signature this 31st day of July, A. D. 1890.

JULIUS PEGEL.

Witnesses:

ADOLPH PETZOLD,
FRANK P. BEAL.
